UNITED STATES PATENT OFFICE.

STEPHEN E. BURKE, OF EDON, AND SOLON W. BURKE, OF WAUSEON, OHIO, ASSIGNORS TO THE BURKE - BOLLMAYER MANUFACTURING COMPANY, OF WAUSEON, OHIO.

SWIVEL FOR WINDMILLS.

SPECIFICATION forming part of Letters Patent No. 761,143, dated May 31, 1904.

Application filed March 17, 1903. Serial No. 148,272. (No model.)

To all whom it may concern:

Be it known that we, STEPHEN E. BURKE, residing at Edon, Williams county, and SOLON W. BURKE, residing at Wauseon, in the county 5 of Fulton, State of Ohio, citizens of the United States, have invented a new and useful Swivel for Windmills, of which the following is a specification.

The invention relates to improvements in 10 swivels for windmills.

The object of the present invention is to improve the construction of swivels for windmills and to provide a simple, inexpensive, and efficient one designed for use in connection with the pull-out wire of a windmill and the operating-wire of a lubricator and adapted to receive the said wires and prevent the same from being twisted by the rotation of the mill-head.

20 A further object of the invention is to provide a device of this character adapted to be attached to either of the said wires and capable of forming a guide for the other wire.

With these and other objects in view the 25 invention consists in the novel construction and arrangement of parts hereinafter fully described, illustrated in the accompanying drawings, and particularly pointed out in the claims hereto appended, it being understood 30 that changes in the form, proportion, and minor details of construction within the scope of the claims may be resorted to without departing from the spirit or sacrificing any of the advantages of the invention.

35 In the drawings, Figure 1 is a perspective view of a portion of a windmill provided with a swivel constructed in accordance with this invention. Fig. 2 is an enlarged detail perspective view of the swivel. Fig. 3 is a plan 40 view of the same, the wires being in section. Fig. 4 is a vertical sectional view of the swivel.

Like numerals of reference designate corresponding parts in all the figures of the drawings.

45 1 and 2 designate upper and lower portions of an operating-wire, which extend downwardly from a lubricator 3 to the base of the

tower 4 to enable the lubricator to be operated at the ground or at any other convenient point. The lubricator 3, which may be of any 50 desired construction, is connected with the bearings of the windmill by distributing-pipes of any desired construction; but as the lubricator and the windmill do not constitute any portion of the present invention a detail description of the same is unnecessary. The 55 upper and lower portions of the operating-wire are connected with sections 5 and 6 of a swivel which is hollow to provide a central opening for the pull-out wire 7 of the windmill. The upper section 5 of the swivel is cup-shaped and is provided at its bottom with a central opening 8 for the reception of the lower section 6 of the swivel. The upper section 5 of the swivel is provided at diametrically opposite points with upward extensions 60 65 70 75 80 85 90 95 98 99 100 101 102 103 104 105 106 107 108 109 110 111 112 113 114 115 116 to facilitate the attachment of the lower portion 2 of the lubricator-wire. The lower portion 2 of the lubricator-wire has its upper terminal passed through the perforation or 5 aperture of the lower section of the swivel, and it is twisted around the body portion of the wire at 16, as clearly shown in Fig. 2 of the drawings.

The upper section of the swivel is adapted 10 to rotate on the lower section to permit the upper portion 1 of the operating-wire of the lubricator to rotate around the pull-out wire without causing the wires to become twisted. The swivel, which is located at a point beyond 15 the movable parts of the windmill, is preferably arranged adjacent to the top of the tower; but it may be disposed at any convenient point.

It will be seen that the swivel is exceedingly simple and inexpensive in construction, 20 that it is adapted to be readily applied to either the pull-out wire of a windmill or the operating-wire of a lubricator, and that it will effectually prevent such wires from becoming twisted by the rotation of the head of 25 the windmill.

What we claim is—

1. In a device of the class described, the combination with a windmill having a pull-out 30 wire, and a lubricator having an operating-wire, of a hollow swivel having one of the wires passing through it, said swivel being composed of sections provided with means for the attachment of the other wire, the latter being arranged exteriorly of the swivel, and one of the sections of the swivel being adapted to rotate on the other, whereby the wires are prevented from being twisted by the 35 rotary movement of the head of the windmill, substantially as described.

2. In a device of the class described, the combination of a windmill having a pull-out wire, and a lubricator having an operating-wire, of a swivel having one of the wires passing 40 centrally through it and composed of a cup-shaped section provided with an opening, and a tubular section fitted in the opening of the cup-shaped section, said sections being capable of rotation on each other and provided

with means for the exterior attachment of the 50 other wire, substantially as described.

3. A device of the class described comprising a hollow swivel having a central guide-opening, and composed of a cup-shaped section provided in its bottom with an opening, 55 and a substantially tubular section fitted in the opening of the bottom of the cup-shaped section, and provided with a projecting flange engaging the said bottom, said sections being provided with exterior attachment portions 60 and adapted to turn freely on each other, substantially as described.

4. In a device of the class described the combination with two wires, of a hollow swivel having an opening to permit one of the wires 65 to pass centrally through it and forming a guide for the same, and composed of a cup-shaped section having a central aperture and provided at opposite sides with perforated ears for the exterior attachment of a portion 70 of the other wire, and a tubular section fitted in the aperture of the cup-shaped section, and having a flange provided beyond the cup-shaped section with a perforation for the exterior attachment of the other portion of the 75 wire which is connected with the said ears, substantially as described.

5. A device of the class described comprising a hollow swivel designed to receive and form a guide for a wire, and composed of a 80 cup-shaped section having an opening, a tubular section fitted in the opening and provided with means for engaging the cup-shaped section, said tubular section being provided with a flaring bore, and having a perforation at one side and cut away at the opposite side, substantially as described.

In testimony that we claim the foregoing as our own we have hereto affixed our signatures in the presence of two witnesses.
